POT SCRAPER

Louise M. Jones Foulke, Brooklyn, N. Y.

Application December 31, 1947, Serial No. 143,481

Term of patent 14 years

(Cl. D9—6)

To all whom it may concern:

Be it known that I, Louise M. Jones Foulke, a citizen of the United States, residing at Brooklyn, in the county of Kings, in the State of New York, have invented a new, original, and ornamental Design for a Pot Scraper, of which the following is a specification, reference being had to the accompanying drawing, forming a part thereof.

Fig. 1 is a top plan view of a pot scraper, showing my new design; Fig. 2 is a side elevational view of the same.

I claim:

The ornamental design for a pot scraper, as shown.

LOUISE M. JONES FOULKE.
